(57) **CLAIM**

The ornamental design for an operational mode icon for a display screen of a control unit for a surgical device, as shown and described.

DESCRIPTION

FIG. 1 is top, front, right said isometric view of an operational mode icon for a display screen of a control unit for a surgical device; and,

FIG. 2 is a front view thereof, on an enlarged scale, and the icon is shown separately for clarity of illustration.
The broken line drawing of a display screen in FIG. 1 is for illustrative purposes only and forms no part of the claimed design.
